UNITED STATES PATENT OFFICE.

ALGOT J. E. LARSON, OF JAMESTOWN, NEW YORK, ASSIGNOR TO ART METAL CONSTRUCTION COMPANY, OF JAMESTOWN, NEW YORK, A CORPORATION OF MASSACHUSETTS.

CABINET.

1,329,616.

Specification of Letters Patent.

Patented Feb. 3, 1920.

Application filed August 20, 1915. Serial No. 46,473.

To all whom it may concern:

Be it known that I, ALGOT J. E. LARSON, a citizen of the United States, and resident of Jamestown, in the county of Chautauqua and State of New York, have invented certain new and useful Improvements in Cabinets, of which the following is a specification.

This invention is a sectional case, and while capable of general use is particularly designed for use as a filing case or cabinet of the type employing drawers for containing papers, documents and the like.

Each case section is complete in itself and is therefore capable of use independent of other sections, while at the same time a plurality of sections may be assembled one upon the other so as to form a vertical stack or series of case units.

It is an important feature of the present invention to provide for the convenient assemblage of two or more units or sections, and to insure a rigid and effective interengagement of superimposed units or sections so as to prevent looseness and accidental separation thereof, without requiring the employment of extraneous fastenings, such as bolts, spring clips and the like. In this connection, it is designed to provide such a connection between the rear end portions of superimposed units as to prevent forward and downward tilting and subsequent separation of an upper section when a drawer substantially full of papers is pulled out to a considerable extent from said upper unit or section.

With these and other objects in view, the present invention consists in the combination and arrangement of parts as will be hereinafter more fully described, shown in the accompanying drawings and particularly pointed out in the appended claims, it being understood that changes in the form, proportion, size and minor details may be made, within the scope of the claims, without departing from the spirit or sacrificing any of the advantages of the invention.

In the drawings,

Figure 1 is a perspective view of two superimposed cabinet sections or units embodying the features of the present invention.

Fig. 2 is a sectional view on the line 2—2 of Fig. 1.

Fig. 3 is a sectional view on the line 3—3 of Fig. 2.

Fig. 4 is a perspective view of one of the sections or units with the drawer removed.

Fig. 5 is a detail view of one of the bar elements of the skeleton frame.

Like characters of reference designate corresponding parts in each of the several figures of the drawings.

Referring at first more particularly to Fig. 4 of the drawings, it will be seen that aside from the drawer, the unit or section of the present invention is of skeleton form, and includes a pair of front uprights 1, a pair of rear uprights 2, an upper front cross bar 3, an upper rear cross bar 4, a lower front cross bar 5, a lower rear cross bar 6, lower side bars 7, connecting the respective front and rear uprights, and a top plate 8 connecting the upper front and rear cross bars. The top plate is provided with opposite longitudinal depending flanges 9, which extend for about one-half the height of the unit and are preferably integral with the top plate. At the crossings or intersections of the several parts of the frame, said parts are connected together by spot-welding, and no rivets, bolts or other fastenings are used in the construction of the skeleton frame. The front uprights 1 and upper cross bar 3 are formed from a single metal strap or bar bent to produce the uprights and the cross bar. The lower end of each front upright extends below the bottom front cross bar to form a depending foot 10. The front half of the lower projecting end of each front upright 1 is notched or cut away as at 11 so as to reduce the width of the foot, for a purpose as will be hereinafter explained. At the top of each front upright 1, there is a notch 12 intersecting the rear edge of the member and terminating about midway between the front and rear edges of said member. It will of course, be understood that there is a similar notch at each side of the section or unit, and the two notches 12, as well as the two notches 11, are formed in the strap or bar before it is bent. The top plate 8 and its flanges 9 lie inside of the skeleton frame, so that the seats formed by the notches 12 are on the outside of the unit.

Each rear upright 2 is extended below the section or unit so as to form a foot 13, the rear portion of which foot is provided with

a substantially V-shaped notch 14, which produces a dove-tail shaped foot, or a foot which is wider from front to rear at its base than at its top, with the rear edge or 5 wall of the foot inclining upwardly and forwardly. At the top of each rear upright 2, there is a notch 15 intersecting the front edge of the upright and having the shape and dimensions of the foot 10 13. The rear uprights 2 and the rear cross bar 4 are formed from a single strap of metal, as described, for the front uprights and front top cross bar.

The front lower cross bar 5 is a plain bar 15 and is applied to the under sides of the lower side bars 7, which are angle bars. The lower rear cross bar 6 is an angle bar, with the side bars 7 fitting inside thereof so that the horizontal flanges or members of 20 the side bars are smooth or free from projections, so as to form a guideway for the drawer 16 which may be of any suitable or preferred construction. However, the sides 25 17 of the drawer need not be the full height of the drawer, as it is sufficient that they merely overlap the side flanges 9 of the top plate 8, whereby a considerable amount of metal is saved in the construction of the drawer, as well as in the construction of the 30 skeleton frame of the unit or section.

If desired, a suitable stop 18 may be provided upon the under side and at the front portion of the top plate 8, so as to limit the outward movement of the drawer. The 35 drawer may be inserted into the skeleton frame by first tilting the same so as to pass its upper rear end inwardly beneath the stop 18, and then brought down to a substantially 40 horizontal position and pushed into the frame.

It will now be understood that each section or unit is complete in itself and may be used entirely independent of any other section, the front and rear feet 10 and 13 supporting the device in a slightly elevated position so as to obtain the advantages of the so-called sanitary furniture.

A second unit or section may be placed upon the top of a lower section, by placing 50 the rear feet 13 astraddle of the rear portion of the top of the lower section with the upper section inclined upwardly, and thereafter swinging the upper section downwardly so as to bring the feet 13 into the 55 V-shaped seats or notches 15 and the front feet 10 into the front seats or notches 12. When thus assembled, the feet of the upper section straddle the top of the lower section and prevent sidewise displacement of the 60 sections. Furthermore, the feet of the upper section fit in the seats or recesses at the top of the lower section and prevent separation of the sections in a direction front and rear thereof. This interlocking of the sections 65 is accomplished without extraneous fasten-

ings, therefore the sections may be very conveniently assembled and taken apart without requiring the removal or the manipulation of any fastening devices, and therefore it does not require the employment of 70 skilled labor for the assembling and taking down of a plurality of units or sections of the present invention.

It will here be noted that the joint between the upper and lower rear uprights 2 75 is Z shaped, whereby the inclined wall of one of the parts overhangs the inclined wall of the other part and prevents upward separation of the parts.

When two sections have been thus assembled, the drawer of the upper section may be drawn out to its limit, and although it may be heavily weighted with papers or other objects, the upper section will be positively held against tilting forwardly and 85 downwardly by reason of the fact that the dove-tailed rear feet 13 are overhung by or engage beneath the under cut rear wall of the rear notch or seat 14.

Having thus described the invention, what 90 is claimed is:—

1. A cabinet section or unit comprising a skeleton frame made up of uprights, cross bars and side bars, the front uprights and top front cross bar being bent from a single 95 bar having its ends projecting below the bottom of the frame and reduced in width to form feet, said bar being provided with a pair of notches intersecting its rear edge and disposed at the top of each side of the 100 frame, each notch constituting a seat of the shape and size of one of the lower feet, the rear uprights and rear top cross bar being bent from a single metal bar, the ends of the bar depending below the frame and each 105 provided in its rear edge with a dove-tailed notch producing a dove-tailed foot, and the bar being provided with a pair of notches intersecting its front edge and located at the tops of the sides of the frame and shaped to 110 correspond to the dove-tailed feet.

2. A cabinet section or unit provided with front uprights and a top front cross-bar bent from a single bar having its ends projecting below the bottom of the frame and reduced 115 in width to form feet, said bar being provided with a pair of notches intersecting its rear edge and disposed at the top of each side of the section, each notch constituting a seat of the shape and size of one of the 120 lower feet, and rear uprights and a rear top cross-bar bent from a single metal bar, the ends of the bar depending below the frame and each provided in its rear edge with a dove-tailed notch producing a dove-tailed foot and said bar being provided with 125 a pair of notches intersecting its front edge and located at the tops of the sides of the section and shaped to correspond to the dove-tailed feet.

3. The combination of superimposed cabinet sections or units, the upper unit being provided at each of its front and rear ends with a bar extending around and embracing the top and opposite upright sides of the unit and having its ends projecting below the unit and lapping the side walls of the lower unit, said lower unit being provided with front and rear external seats receiving the depending ends of the respective front and rear bars.

4. A filing case consisting of a plurality of units, each of which includes a framework comprising similar vertically-disposed front and rear frames of strap-iron and longitudinal connecting pieces forming horizontal slide-ways, the metal of each frame being cut to form depending lugs flush with the sides of the frame, the front and rear frames being cut away at the upper corners and in the rear and front edges respectively to form openings extending down their sides

adapted to receive the lugs of a superposed unit.

5. A filing case consisting of a plurality of units each of which includes a framework comprising similar vertically-disposed rectangular front and rear frames of strap-iron, longitudinally extending angle-irons forming horizontal slide-ways secured to the lower corner of such frames, and a flanged cover-plate secured to the upper portion of said frames, the metal of each frame being cut to form depending lugs flush with the sides of the frame, and the front and rear frames being cut away at their upper corners and in the rear and front edges respectively to form openings extending down their sides adapted to receive the lugs of a superposed unit.
